MOUNTING BRACKET FOR SILK SCREEN STRETCHING CLAMP

Frederick A. Marett, 212 Seaman Ave.,
Rockville Centre, N.Y.

Filed Sept. 19, 1961, Ser. No. 66,752

Term of patent 3½ years

(Cl. D54—13)

FIG. 1 is a front elevational view of a mounting bracket for silk screen stretching clamp showing my new design;

FIG. 2 is a side elevational view thereof, with the broken line portions omitted for convenience of illustration;

FIG. 3 is a top plan view thereof, as shown in FIG. 2;

FIG. 4 is a sectional view taken along the line 4—4, of FIG. 1 with portions omitted for convenience of illustration, and

FIG. 5 is a sectional view taken along the line 5—5 of FIG. 1.

The dominant features of my design reside in the portions disclosed in full lines in the drawing.

The side and end not shown are substantially the same in appearance as side and end shown.

I claim:

The ornamental design for a mounting bracket for silk screen stretching clamp, substantially as shown and described.
